Patented Sept. 30, 1913.

UNITED STATES PATENT OFFICE.

ADOLF BELER, OF PITTSBURGH, PENNSYLVANIA.

BURNER.

1,074,157.

Specification of Letters Patent.

Patented Sept. 30, 1913.

Application filed November 8, 1912. Serial No. 730,233.

To all whom it may concern:

Be it known that I, ADOLF BELER, a citizen of the United States, residing at Pittsburgh, in the county of Allegheny and 5 State of Pennsylvania, have invented a new and useful Burner, of which the following is a specification.

This invention relates to burners particularly designed for use in connection with 10 water heaters in which hydro-carbon gases are utilized as fuel.

Considerable difficulty has been experienced heretofore in properly commingling the combustible elements of the fuel with 15 the air utilized in conjunction therewith and, as a result, the amount of heat obtained has not been as great as desired.

One of the objects of the present invention is to provide improved means whereby 20 the combustible gas employed as a fuel is thoroughly broken up and commingled with air supplied thereto, thus producing a highly combustible mixture having the greatest possible value as a heating medium.

25 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

30 In the accompanying drawings the preferred form of the invention has been shown.

In said drawings:—Figure 1 is a view partly in front elevation and partly in section of the burner. Fig. 2 is a section on line A—B Fig. 1, the upper portion of the tubular standard being shown in section. Fig. 3 is a section on line C—D Fig. 1. Fig. 4 is a view of the lower end portion of the separating plate. Fig. 5 is a section on line E—F Fig. 2.

Referring to the figures by characters of reference 1 designates a portion of the base 50 ring of the burner, this ring constituting means for distributing gas to a plurality of burners mounted on the ring. Inasmuch as all of the burners are of the same construction, it is not deemed necessary, in the present case, to describe and illustrate more than one of them.

A nipple 2 is screwed or otherwise connected to the ring 1 and extends upwardly therefrom, and surrounding this nipple and concentric therewith is an upstanding flange 3 formed on the top plate 4 of the burner ring. An annular shoulder 5 is formed upon the lower portion of the nipple and supports the base 6 of a tubular standard 7, said base, as shown in Fig. 3, being in the form of a spider having air inlet openings 8. A collar 9 is adjustable vertically upon the enlarged lower portion 10 of the standard 7 and has an annular flange 11 extending downwardly therefrom, this flange being so positioned as to completely surround the flange 3 when the collar is lowered to its greatest extent. A set screw 12 is carried by the collar and engages the enlargement 10, this screw serving to hold 75 the collar against movement relative to the standard. It will be obvious that by adjusting the ring, the distance between the flanges 3 and 11 can be increased or diminished and the supply of air admitted to the inlets 8 thus regulated.

The standard 7 is provided, at its upper end, with a head 16 having an inclined open face designed to support a plate 14 having transversely arched parallel portions outstruck therefrom and extending practically throughout the length of the plate. The side and bottom edge portions of the plate 14 are clamped upon the rectangular upper end 16 of the standard by a cap 17 so shaped 85 as to bear tightly upon said edge portions of the plate and upon the upper edge portion of the head 16, this cap being held in place in any preferred manner, as by means of screws 18 engaging the sides of the head 95 16. An air conducting hood 19 is arranged along the back of the head 16 and discharges, at its upper end, into the cap 17 between the upper wall of the cap and the upper edge of the plate 14. The hood is 100 preferably tapered toward its upper end. Each of the arched portions, which have been indicated at 20, is provided with a longitudinal series of transverse slits 21 constituting ports through which gas is free to 105 escape into the mixing chamber formed in the cap 17. One or more outlets 22 are provided in the front face of the cap 17 near its upper edge, these outlets being overhung by a deflecting flange 23 or the 110 like.

It will be understood of course that gas

will be directed through the middle tube into the lower end of the standard 7 where it will commingle with air entering the standard through the inlets 8. This mixture of air and combustible gas will flow upwardly within the standard and pass through the head 16 and against the plate 14. The gas flows into the arched portions 20 and from the ends thereof, the principal 10 portion of the mixed gas and air, however, escaping through the slits 21 in thin sheets and into the cap 17. These sheets will strike the inner surface of the cap and be deflected upwardly. Obviously, a thorough 15 mixing of the combustible gas and the air is thus effected. Before the mixture passes through the openings 22 it becomes commingled with a fresh supply of air admitted to the cap from the hood 19.

20 What is claimed is:—

1. A burner including a base ring, a standard, means for directing combustible gas from the ring into the standard, said standard having an air inlet at the bottom 25 thereof, an upstanding flange spaced from and surrounding the standard, and means adjustable longitudinally of the standard and relative to the flange for controlling the supply of air to the inlet.

30 2. A burner including a standard, having a head at its upper end provided with an open face, a cap mounted on the head and having an outlet, said cap being adapted to receive fuel passing through the head, 35 and means for supplying fresh air to the interior of the cap and above the head.

3. A burner including a standard, having a head at its upper end, said head including an open face, a cap mounted on 40 the head and having an outlet, said cap being adapted to receive fuel passing through the head, and a separating plate mounted on the head and within the cap, said plate having transversely bowed out 45 standing portions formed with outlet slits extending transversely of the head.

4. A burner including a standard having a head provided with an open face, means coöperating with the head for forming a mixing chamber above the head, said chamber having a fuel outlet, a plate upon the head and having parallel outstruck portions formed with slits for the passage of sheets of gas into said mixing chamber, said 55 slits being arranged transversely of the head.

5. A burner including a standard having

a head, a cap upon the head and forming a mixing chamber, a plate seated in the mixing chamber and including means for directing separate sheets of gases against the cap, and means for directing fresh air into the upper portion of the cap.

6. A burner including a standard having a head at its upper end, means coöperating 65 with the head for forming a mixing chamber, a plate within said chamber and including outstruck portions having parallel slits therein for the escape of gases, there being an outlet adjacent the upper end of 70 the chamber, and means for directing fresh air into said chamber.

7. A burner including a standard having a head including an open face, a cap bearing on the head and having an outlet near 75 its upper end, and a plate clamped upon the head by the cap, said plate extending over the open face and having outstruck portions provided with gas outlets.

8. A burner including a standard having 80 a head including an open face, a cap bearing on the head and having an outlet near its upper end, a plate clamped upon the head by the cap, said plate extending over the open face and having outstruck portions provided with gas outlets, and means for directing fresh air into the mixing 85 chamber and above said plate.

9. A burner including a standard having an inclined upper end portion constituting 90 a head, said head including an inclined open face, a plate mounted on said face and having parallel outstruck portions provided with transverse slits, a cap extending over and surrounding the plate and secured 95 to the head, said cap having a fuel outlet, and means for directing fresh air into the cap.

10. A burner including a standard having a head at its upper end, said head including 100 an inclined open face, a cap mounted on the head and having an outlet, said cap being adapted to receive fuel passing through the head, a separating plate mounted on the head and within the cap, and 105 means for supplying fresh air to the interior of the cap.

In testimony that I claim the foregoing as my own, I have hereto affixed my signature in the presence of two witnesses.

ADOLF BELER.
